UNITED STATES PATENT OFFICE.

THOMAS FINIGAN, OF PATERSON, NEW JERSEY.

BRAIDING-MACHINE.

SPECIFICATION forming part of Letters Patent No. 416,905, dated December 10, 1889.

Application filed September 23, 1887. Serial No. 250,521. (No model.)

To all whom it may concern:

Be it known that I, THOMAS FINIGAN, a citizen of the United States, residing at Paterson, in the county of Passaic and State of New Jersey, have invented certain new and useful Improvements in Braiding-Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to machines for making braided cord either with or without a core; or for enveloping wire, or whip-stocks, or other articles with a braided covering. It has especial reference to machines of this 20 class in which two sets of bobbins move in opposite directions for the purpose of interlocking or lacing the threads to form a braid.

The object of my invention is to dispense with many parts of the old machines in common 25 use and to simplify the whole, producing a machine which can be run at a much greater velocity than has heretofore been possible, and thereby turning out more goods in a given time.

30 My invention consists, mainly, in a set of bobbins which are carried in a circular path in one direction and a set of shuttles which are driven in the opposite direction, the shuttles being guided in annular grooves and 35 crossing the path of the threads from the bobbins, suitable means being provided for causing the shuttles to pass alternately above and below the bobbin-threads, and thereby interlace with them.

40 In the accompanying drawings, Figure 1 is an end view of a braiding-machine embodying my improvements. Fig. 2 is a side elevation thereof; Fig. 3, a plan view; Fig. 4, an enlarged plan view, partly broken away; and 45 Fig. 5, a vertical cross-section of the bobbin-carrier, shuttles, and attendant mechanism; Figs. 6 and 7, an elevation and plan of one of the shuttles. Fig. 8 is a detail of the bobbin, stud, and tension-spring.

50 Similar letters indicate like parts in all the figures.

The frame of the machine may be conveniently composed of two forked ends A, united by three rails or cross-bars a a' a^2 , as shown. Between the lower and middle rails a' a^2 is an upright A', and from the upper rail rise two standards A² to support the reeling mechanism. Journaled in one of the ends A and in the upright A' is a shaft B, furnished with fast and loose pulleys b b' . On the inner end of this shaft is a bevel-gear C, meshing with two bevel-gears D E, one above and one below the axis of the shaft B and both of the same size. The bevel-gear D is secured to the lower end of a tubular shaft D', which is mounted to revolve in a sleeve F, supported by the rail a' . On the upper end of this shaft is mounted the bobbin-carrier, which consists of a series of arms d, radiating to a ring D², concentric with the shaft D'. This ring is 70 preferably broad and flat, as shown, and upon it at equal distances are mounted the bobbins G upon stationary studs g near the outer edge of the ring D².

One end of a tension-spring G' is secured 75 below the bobbin G, the other end pressing upon the thread on the bobbin. The end of the spring is clamped between the ring D² and a collar on the stud g, as shown in Fig. 8. Near the bobbin is a U-shaped bracket H, 80 rising from the outer edge of the ring D². In the upper end of each arm of the bracket is an eye h, through which the thread from the bobbin G is passed and then taken to an eye at the center of the machine in line with 85 the shaft D'. The advantages of this construction are greater simplicity and cheapness of manufacture by doing away with the studs and nuts usually employed to fasten the ends of these springs and a more uniform 90 tension on the thread at all times, whether the bobbin be full or nearly empty.

In radial line with each of the U-shaped brackets H is an upright I, fastened upon the ring D². These uprights support a 95 smaller flat ring D³, concentric with ring D².

In the under face of ring D³ is an annular groove d'. Directly below it, in the upper face of ring D², is a similar groove d², of the same diameter as groove d'. Seated loosely 100 in the circular raceway formed by these grooves are several shuttles K, equal in num-

ber to the bobbins G, each consisting of a frame curved to fit the grooves d' d^2 and pointed at one end, the edges being rounded and smooth. In the frame is mounted a bobbin k, which is centered at one end upon a spindle k' and at the other upon a rounded stud k^2 . A spiral spring k^3 encircles the spindle k' and presses the end of the bobbin against the frame of the shuttle, thereby producing a tension upon the thread as it unwinds from the bobbin k. The spindle k' is pivotally attached to the frame K, preferably by the pin upon which the hook-shaped wire k^4 is pivoted to the frame, said wire being for a purpose hereinafter set forth. The pivoting of the spindle allows it to be turned outward when it is desired to remove the bobbin.

As the rings D^2 D^3 form part of one structure, being united by the uprights I, it is evident that if left to themselves the shuttles would be carried around with the rings. To prevent this and to make them run in the opposite direction, there is provided inside of the tubular shaft D' a smaller tubular shaft E', upon which is mounted the bevel-gear E. The upper end of this shaft projects above the end of the shaft D' and carries a set of radial arms or sweeps e—one for each shuttle—reaching out over and close to the ring D^2 . At the outer end of each sweep is a small triangular head e' ; which travels in an annular groove d^3 , formed in the upper face of the ring D^2 outside of and concentric with the groove d^2 . These radial sweeps e come in contact with the rear ends of the shuttles K and drive them in a circular path in a direction opposite to that of the ring D^2 and bobbins G and at the same speed.

The operation of the above-described parts is as follows: Power being applied to the fast pulley b, the shaft B and bevel-gear C are rotated, thereby driving the bevel-gears D' E in opposite directions. The rings D^2 D^3 and the bobbins G revolve in one direction, the sweeps e and the shuttles in the other. The point at which all the threads meet is so located that the threads from the bobbins G pass normally above the points of the shuttles K, between the rings D^2 and D^3 , as shown at the left hand of Fig. 5; but at every alternate passing of shuttle and bobbin the bobbin-thread must be made to pass below the shuttle in order to interlace with the shuttle-thread to form the braid. To accomplish this result, I attach to the upper rail a a set of curved arms L, equal in number to the bobbins G and extending to equidistant points around the circumference of ring D^3 . The ends of these arms L lie close to the ring D^3 , between it and the bobbins G, being inclined downward to a point below the nose of the shuttle. These inclined portions are so located that at every alternate meeting of shuttle and bobbin the bobbin-thread strikes the inclined arm L and is forced down below the nose of the shuttle, and so passes under it, thereby

interlacing with the shuttle-thread. The triangular shape of the head e' of the sweep e prevents the thread from catching on the sweep. It will be noticed that the bobbin-thread is subjected to very little friction when it passes the shuttles, because, although it is crowded into one of the grooves d' d^2 in the upper or lower rings D^3 D^2 , yet as these rings are moving with the thread there is no rubbing of the thread against them. The only friction upon the thread is that due to the smooth rounded edge of the shuttle, which is very slight. This feature reduces the danger of breaking a thread, which is far more imminent in machines where the thread is swept around in contact with a stationary ring, or a shuttle-carrier moving in the opposite direction. In fact, the crowding of the thread into the groove d' or d^2 enables it to pass the shuttle more evenly and with less slack, for the edges of the groove take hold of the thread and aid in carrying it along. This operation is also assisted by the upright I, just in front of which the thread passes, and which gives the thread a firm bearing close to the shuttle.

Whenever the bobbin-thread has passed over or under a shuttle, there is a slight amount of slack to be taken up. This is done by a U-shaped spring M, one end of which is fastened to the lower part of the bracket H, while the free end rests with some pressure upon the bobbin-thread where it crosses the space between the two upright arms of the U-shaped bracket H. These springs also serve to stop the machine when the thread breaks. In such an event the free end of the spring immediately flies down to the ring D^2 , as shown at the right hand of Fig. 5, and being long enough to project beyond the edge of the ring it comes, in a half-revolution of the ring, in contact with one of two fingers N, projecting upward from a rock-shaft O, mounted in suitable bearings on the rail a'. At one end of this rock-shaft is a downwardly-extending finger N', engaging with a hook p upon a shipper-bar P. A spiral spring p' exerts a constant pressure upon the shipper-bar, tending to throw the belt over on the loose pulley. When the rock-shaft O is partially rotated by the end of spring M coming against the finger N, the shipper-bar is released and the belt is shifted, thereby stopping the machine. I also provide means for stopping the machine in case a shuttle-thread breaks. A wire k^4 is pivoted at one end to the inner side of the shuttle and extends along above the axis of the bobbin to the other end of the shuttle, where it is bent at about right angles and passes through a slot in the shuttle. The extreme end of the wire is bent downward to prevent it from being drawn through the slot. The thread from the shuttle-bobbin passes up over this wire k^4 and keeps it drawn inwardly, as shown in full lines in Fig. 7 and at the righthand of Fig. 5. When the shuttle-thread breaks, the wire k^4 is free to move, and cen-

trifugal force throws it outward, as shown in dotted lines in Fig. 7 and at the left hand of Fig. 5. In this position it comes almost instantaneously in contact with a finger q , projecting 5 up from one end of one of a set of short rock-shafts Q , turning in bearings in the brackets H and the uprights I . On the outer ends of these rock-shafts are cams q' , which, when turned downward by the wire k^4 striking the 10 finger q , come, in a half-revolution of the ring D , in contact with one of the fingers N , and stop the machine in the manner heretofore described.

It is sometimes desirable to cover a core 15 with a lapping of thread or wire before the braided covering is put on. To accomplish this, I extend the shaft E' through the lower rail a^2 and mount upon its end a head R , carrying a disk R' and one or more guides r . On 20 the disk are mounted one or more bobbins R^2 , the thread from which passes through the guides r . When the shaft E' revolves, the thread from the bobbin R^2 is wound upon the core, which then passes up through the hollow shaft E' to the point where the braided 25 covering is applied. For reeling up the completed cord, motion is transmitted through a pair of bevel-wheels $s s'$ to an upright shaft S , provided with a worm which meshes with 30 a worm-gear T , mounted upon a stud. A pair of gears $t t'$, which can be changed to give different speeds when desired, communicate motion to a shaft U , on which is a winding-drum u , around which the cord is wrapped 35 several times, passing at every turn over a grooved drum v , loosely mounted on a shaft V . The cord then goes to a reel w on a shaft W , which is rotated by a band from a wheel on 40 the shaft U . The band is loose enough to slip when the reel fills up, so as to prevent winding the cord too tight and allow for the variation in the diameter of the reel.

The advantages of my machine are several. I arrange the two sets of bobbins in substantially the same horizontal plane. The thread 45 makes but one turn in going from the bobbin to the point where the braid is formed, thus reducing the friction to a minimum. Again, the movements of the bobbins and shuttles 50 are continuous and in circular paths, which is the most economical mode of applying the power. The machine is composed of but few parts, all in full sight and easily repaired. It is well balanced and can be run at least eight 55 times as fast as the ordinary machines heretofore in use.

Having thus described my invention, what I claim, and desire to secure by Letters Patent, is—

60 1. A braiding-machine having a bobbin-carrier provided with two guides arranged one above the other and forming a circular raceway, a set of shuttles supported in the raceway by having their opposite edges engaged with the guides, and means, substantially as described, for driving the bobbin-carrier and the shuttles in opposite directions

in concentric circles, substantially as described.

2. The combination, with a tubular shaft 70 carrying a ring adapted to receive a set of bobbins and provided with a continuous circular raceway concentric with the path of the bobbins, of a set of shuttles seated in said raceway and lying in the same horizontal 75 plane as the bobbins, a shaft having arms for driving the shuttles, and means for rotating the two shafts in opposite directions, substantially as described.

3. The combination, with a tubular shaft 80 carrying two annularly-grooved rings, forming a continuous circular raceway and adapted to receive a set of bobbins, of a set of shuttles seated in the raceway, a shaft carrying a set 85 of arms for driving the shuttles, and means for rotating the shafts in opposite directions, substantially as described.

4. In a braiding-machine, the combination, with the ring D^2 , having the annular groove d^2 , and the ring D^3 , having the annular groove 90 d' and united by the uprights I , of the curved shuttles K , seated loosely in the grooves d^2 and d' , and means for driving the shuttles along the annular grooves, substantially as described. 95

5. The combination, with the rings $D^2 D^3$, carrying the bobbins G and having the annular grooves $d' d^2 d^3$, of the curved shuttles K , the sweeps e , having the triangular heads e' traveling in the groove d , and means for 100 revolving the bobbin-carrying rings and the shuttles in opposite directions, substantially as described.

6. In a braiding-machine, the combination, with the rings $D^2 D^3$, united by the uprights 105 I and provided with the annular grooves d' d^2 , and having the bobbins G mounted on the ring D^2 , of the U -shaped brackets H , the shuttles K , seated in the grooves $d' d^2$, the sweeps e , the arms L , having inclined ends, 110 and means for revolving the rings and the sweeps in opposite directions, substantially as described.

7. The combination, with the rings $D^2 D^3$, adapted to receive the bobbins G , of the shuttles K , the sweeps e , the stationary arms L , having inclined ends lying close to the edge of the ring D^3 and projecting downwardly between said ring and the bobbins G , and means for revolving the rings and the sweeps 115 in opposite directions, substantially as described. 120

8. The combination, with a suitable supporting-plate, of a stud g , adapted to receive a bobbin G , and a tension-spring G' , having one end clamped between the supporting-plate and a collar on the stud and its free 125 end lying near the stud g , substantially as described.

9. The combination, with the ring D^2 , carrying the bobbin G , of the U -shaped bracket H , the take-up spring M , having its free end passing between the arms of the bracket, the rock-shaft O , having the fingers $N N'$, adapted 130

to be engaged by the end of the spring, and the spring-actuated shipper-bar P, having the hook p, substantially as described.

10. As a stop-motion for braiding-machines, 5 the combination, with the bobbin-carrier, of a shuttle provided with a loosely-pivoted hook-shaped wire, over which the thread passes, a rock-shaft mounted on the bobbin-carrier, a finger on said rock-shaft lying near 10 the path of said shuttle, a cam on the end of said rock-shaft, a spring-actuated shipper-bar, and intermediate mechanism adapted to be actuated by said cam and release the shipper-bar, substantially as described.

11. The combination, with the rings D² D³, 15 of the shuttles K, each having a hook-shaped wire k⁴, pivoted to the inner side of said shuttle above the axis of the shuttle-bobbin, with its free end passing through a slot to the outside of the shuttle, a rock-shaft Q, mounted 20 on the ring D² and having finger q and cam q', rock-shaft O, having fingers N N', and shipper-bar P, engaged by said finger N', substantially as described.

12. In a braiding-machine, the combination, 25 with the shafts D' E', the bobbin-carrier, circular raceway, and shuttles, of the head R, mounted upon the shaft E' and carrying one or more bobbins R², for the purpose of winding a layer of thread upon a core before the 30 braided covering is applied, substantially as described.

13. A braiding-machine having a bobbin-carrier provided with a circular raceway for the shuttles, said raceway consisting of two 35 concentric guides to receive the shuttles, arranged one above the other, so that the thread from the bobbin passes between said guides to the point of braiding, substantially as described.

In testimony whereof I affix my signature in presence of two witnesses.

THOMAS FINIGAN.
